UNITED STATES PATENT OFFICE.

HENRY C. TRIPP, OF AUBURN, NEW YORK.

DUMP-WAGON.

No. 833,764.

Specification of Letters Patent.

Patented Oct. 23, 1906.

Application filed November 17, 1905. Serial No. 287,867.

To all whom it may concern:

Be it known that I, HENRY C. TRIPP, of Auburn, in the county of Cayuga, in the State of New York, have invented new and useful Improvements in Dump-Wagons, of which the following, taken in connection with the accompanying drawings, is a full, clear, and exact description.

This invention relates to certain improvements in dump-wagons of the class set forth in my Patent No. 756,912, issued April 12, 1904, in which a single chain is passed under one of the doors and connected to the other door for controlling the operation of said doors, which allows the chain to swing with the doors in close proximity to or across the discharged load, and therefore portions of the chain necessarily drag through the load as the wagon is drawn forwardly. This causes the chain to be more or less clogged with mud or other sticky substance which may be conveyed in the wagon, and I have found that in cold weather this mud accumulates upon the chain to such an extent as to interfere with its free operation. In my present invention I have sought to overcome this difficulty by supporting the intermediate portion of the chain upon suitable sheaves at each end of the box, and instead of passing the chain under the doors it is extended forwardly through and along one side of the box some distance above the bottom from front to rear and has its front end attached to a vertical or upright winding-drum at the right-hand side of the longitudinal center and at the front of the front end of the box, thereby bringing the greater portion of the chain wholly above the bottom of the doors. The dumping-ground where the material conveyed by the wagon is usually discharged is generally very uneven, and it not infrequently happens that the open doors encounter obstructions while the wagon is being drawn forward, thereby subjecting said doors to a severe strain and making it difficult to draw the wagon forward.

One of the objects of my invention, therefore, is to provide means for elevating both doors simultaneously at the outer sides of the box, although the essential purpose is to control the operation of the doors by a single chain running from front to rear along the side of the box above the bottom.

A further object is to provide a vertical winding-drum for the chain with a ratchet and pawl operated manually, so as to obtain

a rapid closing of the door by a continuous revolution of the drum or by a series of forward and backward movements of the lever upon which the pawl is mounted.

60

A still further object is to provide the lever with means for locating the pawl out of action and to provide the drum with an additional ratchet and pawl, which latter may be thrown out of action by the foot of the driver, thus making it possible to release the doors either by the manually-operated pawl or by the foot-pawl.

6

Another object is to arrange the sides of the box in downwardly-diverging planes, so as to permit the load to free itself more readily on the discharge.

70

Other objects and uses will be brought out in the following description.

In the drawings, Figure 1 is a top plan of my improved dump-wagon and the various improvements used in connection therewith. Fig. 2 is a side elevation of the parts seen in Fig. 1. Figs. 3 and 4 are respectively front and rear elevations, particularly in section, of the parts seen in Figs. 1 and 2. Fig. 5 is a transverse sectional view through the box, showing the bottom doors as drawn upwardly at the sides of the box.

75

In demonstrating the practicability of my invention I have shown a dump-box consisting of upwardly-converging sides 1, front and rear ends 2 and 3, and swinging bottom doors 4 and 4', which in this instance are normally disposed in a horizontal position when closed. 90 The sides 1 are each provided with a series of, in this instance, three hinge-straps 5, having their lower ends lying in about the same plane as the lower edges of the sides and provided with hook-shaped bearings 6, which are open at the top to receive the hinge-pins 7 on the adjacent edges of the doors 4 and 4', said hinge-pins 7 being provided on the ends of suitable hinge-straps 7', which are secured to the bottoms of the doors in any well-known manner, not necessary to further illustrate or describe. These side pieces 1 extend forwardly and rearwardly some distance beyond the front and rear ends 2 and 3, the forward extensions being provided with a suitable bolster 8 and cut-out 9, the latter being located between the bolster and front end of the box to permit the wheels (not shown) to turn under the extensions and in front of the box proper, while the rear extensions are provided with a bolster 10 and a downwardly-inclined ledge or shelf 11, the bolster 10 serv- 105

95

100

105

110

ing to support the rear axle, (not shown,) and the shelf or ledge 11 serves as a brace between the sides and also allows any accumulation of dirt thereon to readily slide off.

5 The front extensions of the sides are braced against lateral compression by upright transverse bars 12 and 13 and a seat-supporting bar 14, sufficient space being left between the bars 12 and 13 to form a convenient tool-box 10 and foot-space for the driver in front of the cut-out 9.

15 The bottom doors 4 and 4' extend under the lower edges of the sides and ends of the box in a substantially horizontal plane when closed and meet at substantially the longitudinal center of said box and are each provided at its ends near its meeting edges with a pair of sheaves or rollers 15, around the under side of which is passed a winding-cable, 20 as a chain 16, having one end attached to a vertical winding-drum 17 near the right-hand side of the box and its rear end secured to an anchor 18 on the same side of the box just outside of the rear end 3 and above the 25 bottom doors and shelf 11.

30 The lower end of the drum 17 is stepped in a suitable plate 19 on the bolster-bar 8 and is provided with a ratchet-wheel 20, rigid thereon and engaged by a foot-pawl 21. A portion of this drum is journaled in the arms, as 35 22, of a U-shaped bracket 23, which is secured to the adjacent side 1 of the box in front of the seat-support 14, said arms 22 being spaced some distance apart vertically to receive the winding of the chain 16. A second ratchet-wheel 24 is secured to the upper end of the drum directly above the upper arm 22 and is normally engaged by detent 25 and hand-pawl 26, the latter being mounted upon 40 a hand-lever 27, which is loosely journaled upon the upper end of the drum 17 directly above the ratchet-wheel 24.

45 The lever 27 is provided with a link 28, which is adapted to be hooked over the adjacent end of the pawl 26 to hold said pawl in its inoperative position when it is desired to release the bottom doors to discharge the load, it being apparent that the pawls or detent 21 and 25 are still in holding engagement with their respective ratchet-wheel 20 and 24.

55 If it is desired to release the doors, the hand-lever 27, with its pawl held out of operative position by the ring 28, may be swung around in the direction indicated by arrow X until the biting end of the pawl 26 engages the pawl 25 inside its pivot, thereby throwing it out of action, whereupon the foot-pawl 21 may be kicked out of operative position, 60 thereby freeing the drum and releasing the doors, or the foot-pawl 21 may be held out of action by the foot, and the lever 27, with its pawl 26, locked in its inoperative position, may be swung around in the manner described to force the pawl 25 out of action, 65

which will also release the drum 17 and allow the doors to open.

As previously stated, the front end of the cable or chain 16 is attached to the drum 17 and extends rearwardly therefrom over a 70 swinging idler 30 and then downwardly under the sheave 15 on the underlying door 4, thence upwardly over a suitable sheave 31 on the front end 2 of the box, thence downwardly under the sheave 15 on the front end of 75 the door 4', thence upwardly over one or more sheaves 32 on or near the front end or side of the box, said cable passing through the front extension of the adjacent side, and thence rearwardly along said side through a 80 sheave 33 in an opening in the rear extension of the box, after which it passes downwardly under the sheave 15 on the rear end of the door 4', thence upwardly over a sheave 34 on the rear end of the box and downwardly under the sheave 15 on the rear end of the door 4 and has its rear end attached to the anchor 18 on the same side of the box near which the drum 17 is located. It therefore follows that the front and rear ends of the chain or cable 90 draw transversely at the front and rear ends of the box, while the intermediate portion of said cable travels along and in close proximity to the outer face of one side of the box opposite to that near which the ends of the cable 95 are attached. By this arrangement the greater portion of the cable is always out of the way of the load and is less liable to accumulate mud or other material which might interfere with its operation. 100

The means for raising the doors upwardly at the outer sides of the box is shown as consisting of the rock-shaft 35, which is journaled in the front extensions of the sides 1 in front of the transverse bar 13 and provided with 105 upwardly-projecting arms 36 and 37, to which are attached the front ends of opposite cables 38 at the outer sides of the box, one for each door, each cable rendering over suitable sheaves 39 and having pendent ends 110 which are attached to the opposite ends of its corresponding door, as best seen in Fig. 2.

One of the arms 36, preferably that at the left side of the box, is extended upwardly some distance for forming a handpiece 41, 115 which is within convenient reaching distance of the seat, and when it is desired to raise the door after the load has been discharged therefrom the lever 41 is thrown forwardly and may be engaged with suitable shoulders or detents 42, as best seen in Figs. 1 and 2, for holding the doors in their elevated position, as seen in Fig. 5. This operation not only draws the doors upwardly clear of the discharged load, but also causes the inner 120 faces of the doors to scrape against the lower edges of the sides of the box, thereby removing any dirt which may adhere to the doors, the latter being guided in their vertical movement between flanged rollers 44, which are se- 125 130

cured to and project outwardly from the opposite sides of the box and serve to register the hinge-pins 7 with the open sides of their respective bearings 6, when the doors are allowed to drop by the disengagement of the lever 41 with the detents 42.

What I claim is—

1. In a dump-wagon, a box having swinging bottom doors hinged to its sides and meeting at substantially its longitudinal center, a pair of sheaves on each door near its meeting edge, additional sheaves near each end of the box directly over the meeting edges of the doors, an upright drum at the front end of the box near one side, an anchor at the opposite end of the box and a cable passed around said sheaves and having one end attached to the drum and its other end attached to said anchor.
2. In a dump-wagon, a box having swinging bottom doors hinged to its sides and meeting near the longitudinal center of the box, a drum at the front end of the box, an anchor at the rear end of the box, said drum and anchor being located at the one and same side of the longitudinal center of the box, a cable running along the opposite side of the box and having its ends extending transversely thereof and connected respectively to the drum and to said anchor, said transversely-extending portions of the cable being operatively connected to the doors.
3. In a dump-wagon, a box having swinging bottom doors, hinged to its sides and meeting near the longitudinal center of the box, an upright drum at the front end of the box, an anchor at the rear end of the box, said drum and anchor being located at one and the same side of the longitudinal center of the box and above the doors, and a cable running along the outside of the opposite side of the box and having its ends extending transversely and close to the front and rear ends of the box and connected respectively to the drum and to said anchor, sheaves on the ends of the doors engaged by said transversely-extending portions of the cable and additional sheaves on the front and rear ends of the box directly over the meeting edges of the doors and engaged by said transversely-extending portions of the cable.
4. In a dump-wagon, a box having swinging bottom doors hinged to its sides and meeting near the longitudinal center of the box, each end of each door being provided with a sheave near its meeting edge, additional sheaves on the front and rear ends of the box directly over said meeting edges, an upright drum at the front end of the box, an anchor at the rear end of the box, said drum and anchor being located at one and the same side of the longitudinal center of said box, sheaves on the opposite side of the box, and a cable running along the side of the box and

rendering over said sheaves and having its ends attached respectively to the drum and to said anchor.

5. In a dump-wagon, a box having swinging bottom doors hinged to its sides and meeting near its longitudinal center, means for elevating said doors at the outer sides of the box and rollers engaging both ends of said doors to guide them in their vertical movement and prevent their endwise displacement.

6. In a dump-wagon, a box having swinging bottom doors hinged to its sides and provided with open-sided bearings in which the doors swing, said doors being movable upwardly out of said bearings at the outer sides of the box when open, means for effecting such upward movement of the doors and flanged rollers engaging the ends and outer faces of said doors when moved upwardly.

7. In a dump-wagon, a box having swinging bottom doors hinged to its sides and meeting at substantially the longitudinal center of the box and having an independent vertical movement at the outer sides of the box when swung to their open positions, means for controlling the swinging action of the doors separate means for moving them vertically and flanged rollers engaging the ends and outer faces of the doors when elevated.

8. In a dump-wagon, a box having swinging bottom doors hinged at its sides and meeting at substantially its longitudinal center, a pair of sheaves one at each end of the box above the meeting edges of the doors, additional sheaves on one side of the box, one near each end of said box in a plane above the doors, a drum at the front end of the box at one side of the meeting edges of the doors, and a cable passed around said sheaves and operatively connected to the front and rear ends of both doors near their meeting edges, one end of the cable being attached to the drum.

9. In a dump-wagon, a box having swinging bottom doors hinged to its sides and meeting at substantially its longitudinal center, a pair of sheaves, one at each end of the box directly above the meeting edges of the doors, additional sheaves in the side of the box above said doors, an upright drum at the front end of the box and at one side of the meeting edges of the doors, and a cable passed around said sheaves and operatively connected to the opposite ends of both doors near their meeting edges, one end of the cable being attached to the upright drum.

10. In a dump-wagon, a box having swinging bottom doors hinged to its sides and meeting near its longitudinal center, an upright drum at the front end of the box, an anchor at the rear end of the box, said drum and anchor being located at one and the same side of the longitudinal center of the box, sheaves on the opposite side of the box,

a cable running along the latter side around said sheaves and having its ends extending transversely of the box and connected respectively to the drum and to said anchor 5 and also operatively connected to the adjacent ends of the doors and means for raising the doors at the outer sides of the box when swung to their open positions.

11. In a dump-wagon, a box having swinging bottom doors hinged to its sides and meeting near its longitudinal center, means for controlling the action of the doors including a rotary upright drum, a cable connected thereto and to the doors, a ratchet-wheel rigid on the lower end of the drum; a

foot-operated detent normally engaged with said ratchet, a second ratchet-wheel rigid on the drum, a lever loose on the drum and provided with a pawl for engaging the second ratchet-wheel and rotating the drum as the 20 lever is rocked or rotated in one direction and means for holding the pawl of said lever out of operative position when the foot-pawl is tripped.

In witness whereof I have hereunto set my hand this 14th day of November, 1905.

HENRY C. TRIPP.
